(57) **CLAIM**

The ornamental design for a bracket cover applied to a window treatment, as shown and described.

DESCRIPTION

FIG. 1 is a perspective view of a bracket cover applied to a window treatment showing my new design; FIG. 2 is a perspective view thereof in an alternate environment;

FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right side view.

The broken lines illustrate structure or features which form no part of the claimed design.

The drawings include surface shading which represents contour and not surface ornamentation.

1 Claim, 4 Drawing Sheets
